UNITED STATES PATENT OFFICE

2,203,741

REGISTER SYSTEM FOR WATCHMEN

Elvin L. Overstreet, Houston, and Emil L. Harris,
Park Place, Tex.

Application July 24, 1936, Serial No. 92,404

9 Claims. (Cl. 177—360)

The invention relates to an improvement in the construction, arrangement and operation of the key member signal device which is used in connection with register systems wherein a signal is transmitted by a key mechanism only after it has been set by insertion in a plurality of spaced sockets and has its particular application to a watchman's register service.

The invention is in the nature of an improvement of the system disclosed in the patent to Johnson, 1,394,840 granted October 25, 1921.

In the system disclosed in the above entitled patent a plurality of spaced sockets or stations are disposed about the area which the watchman is presumed to traverse periodically. A transmitter station is also positioned on the location whereby a signal is transmitted to a central office for recording to indicate that the watchman has transmitted his signal. The watchman is then provided with a key of the general type shown in said patent which key carries a plurality of tumblers which can be moved step by step from an initial position to a final position by inserting the key in a socket in each of the spaced stations. This arrangement is presumed to compel the watchman to traverse his beat and to insert the key in every station as he passes so that each insertion causes the key to be moved one step. There are a similar number of steps provided in the key in accordance with the number of stations to be used on that particular location, so that by the time the watchman has traversed all of the stations and returned to the transmitter location the key is then in condition to transmit another signal to the central office. In this manner only one transmitter station is required and a considerable saving is in this manner effected.

The present invention directs itself to a particular embodiment in connection with the key and station construction so that there can be no misleading report sent in to the central station and so that the watchman is absolutely compelled to traverse his beat. The present arrangement and construction has been devised because it has been found that in actual practice the keys and the stations have been tampered with by the watchmen in such a manner that the key could be manipulated to transmit the proper signal to the central station without as a matter of fact having traversed his beat or having inserted the key in each of the various stations.

It is one of the objects of the present invention to revise and rearrange the construction and operation of the key member shown in the John-

son Patent 1,394,840 so that the tumbler of such key can only be manipulated by insertion in a sequence of sockets.

Another object of the invention is to provide a register station wherein the key cannot be turned backwardly in the station or removed except by making a proper manipulation thereof.

Still another object of the invention is to provide a register key construction wherein the parts are anchored firmly and securely against misuse.

Still another object of the invention is to provide a stop collar which is anchored securely upon the sleeve member of a register key.

Still another object of the invention is to provide a safety lock in connection with register keys so that if an attempt is made to misuse the key it will be locked in position against further use.

Still another object of the invention is to provide a locking rivet in combination with the parts of a register key to prevent end play of the parts.

Still another object of the invention is to provide elongated openings for the tumbler members in a register key so that a slight mis-alignment of the parts will not interfere with the practical operation thereof.

Other and further objects of the invention will be readily apparent when the following description is considered in connection with the accompanying drawings wherein:

Fig. 1 is a side elevation of a register key constructed in accordance with the invention showing certain portions in section to illustrate the improvements over the prior art.

Fig. 2 is an end view of Fig. 1.

Fig. 3 is a vertical sectional view taken through the inner sleeve member of the key.

Fig. 4 is an end view of Fig. 3.

Fig. 5 is a vertical sectional view of the middle sleeve member of the key construction.

Fig. 6 is an end view of Fig. 5.

Fig. 7 is a broken sectional view of a modified form of the inner sleeve member which is provided with guide registers to prevent misuse of the key.

Fig. 8 is an enlarged sectional view of the end of the key member showing the parts of the present invention and illustrating a safety locking device therewith.

Fig. 9 is a vertical sectional view of the station and socket member in which the key is to be inserted.

Fig. 10 is a front elevation of the socket member with certain portions broken away to illustrate the construction thereof.

30

50

55

Fig. 11 is an enlarged view of a part of the sleeve member showing the elongated openings which may be provided to insure proper operation of the key.

5 The key member is best seen in Fig. 1 and includes a handle 2 which has the shaft 3 thereon upon which the balance of the parts of the key are to be fixed.

10 Telescoped over the body 3 is what may be termed the inner sleeve of the key member 4. This inner sleeve is of peculiar construction in that it has a body portion 5 with a reduced end 6 thereon which is arranged with an opening 7 therein to telescope over the body 3 of the key handle. Opposed openings 8 are provided in this reduced portion 6 and are arranged to receive a through-bolt 9 so that the sleeve 4 will be securely anchored to the body portion 3 and incapable of any sliding or rotating movement relative to the body 3. It is imperative that this sleeve be securely anchored to the body.

15 A shoulder 11 is provided between the reduced area 6 and the body portion 5. The inside of the sleeve 4 is cut away at 12 to provide a thin sleeve-like portion 13. This portion is of considerable length as best seen in Fig. 3 and is provided with a plurality of openings 14 therein. These openings are preferably elliptical in form as best seen in Fig. 11. The elliptical form of opening has been provided so that any variation in the position of the tumbler which is to enter the hole will not interfere with its operation.

20 The openings 14 will be arranged in any desired sequence or combination in order to obtain various sets of signals and in order that one key may not be used in a foreign set of stations.

25 Adjacent the right end of the sleeve 4, as seen in Fig. 3, a stop collar 20 has been securely anchored. This stop collar is shown as being fixed to the end of the sleeve but it is to be understood that it may be made integral therewith or may be affixed by welding, brazing, or riveting as occasion may require. It is important, however, that this collar be securely anchored in place 30 so that it cannot be moved even to a very slight extent.

35 Fig. 8 shows an enlarged view of the sleeve 4 and the collar 20 and illustrates a body of welding material 21 which has been bonded to the surface 22 of the sleeve 4 and to the inclined face 23 of the outer end of the ring 20. This securely anchors the collar to the sleeve 4.

40 Mounted on the sleeve 4 and secured thereto adjacent collar 20 is a ring member 30', as is clearly shown in Figs. 5 and 8. This ring is provided with longitudinal grooves in its surface, which grooves extend but a portion of the length of the ring. The ring is secured to the sleeve 4 in such a manner that the respective 45 grooves are in alignment with the respective series of openings in sleeve 4. The purpose of the provision of this ring will be made apparent as the disclosure progresses.

45 A key stop 25 is shown as projecting from the end of the sleeve 4.

50 The next element to be assembled on the construction is the middle sleeve 30 which is best seen in Fig. 5. This middle sleeve is shown together with ring 30' in Fig. 5 and is shorter than the inner sleeve 4. Sleeve 30 is of uniform thickness throughout its length except for the stop shoulder 31 at the left-hand end on the outside and the inner stop shoulder 32 which defines the difference in diameter between the central passage 33 and the end passage 34 thereof. This

55 middle sleeve is telescoped over the inner sleeve 4 from the left before the inner sleeve is positioned on the handle 2 so that the shoulder 11 abuts against the shoulder 32 as best seen in Fig. 1. This locates the middle sleeve definitely with respect to the inner sleeve.

60 A further stop washer 35 is seen in Fig. 1 which will be positioned against the end 36 of this middle sleeve to fix it permanently in position. The thickness of the stop washer 35 is such that it will bear firmly against the through-bolt 9 and prevent any end play between the sleeves 4 and 30.

65 The middle sleeve 30 has a plurality of openings 38 therein which serve to keep the tumblers 39 in proper alignment and to serve as a guide for the radial movement of the plungers as they move into and out of the openings 14 in the inner sleeve, it being understood that the inner and middle sleeves are relatively rotatable so that the tumblers 39 can be moved over the openings 14 in obtaining different fittings or combinations of the keys.

70 The enlarged end or head 39 of the middle sleeve is provided with an annular groove 40 which is arranged to receive the set pins 41 whereby outer sleeve 50 is anchored thereto. This sleeve is formed with enlarged collar portion 55 which carries the indicia 56 to indicate the setting of the key. The skirt portion 57 on sleeve 50 overlies the head 39 of the middle sleeve and is formed with opposed openings 58 to receive the through-bolt. Openings 59 are also provided in the skirt 57 to receive the set pins 41 which fit into the groove 40 of the middle sleeve.

75 The sleeve 51 is a continuation of outer sleeve 50 and is a particular construction as is best seen in Fig. 1 wherein such sleeve is shown as telescoped over the outer surface of the middle sleeve 30 before the middle sleeve is telescoped over the inner sleeve 4. This outer sleeve 51 has a tumbler housing 61 affixed thereto as seen in Fig. 1. This tumbler housing may be rigidly affixed to the sleeve in any desired manner and may be made integral therewith and encloses the springs 62 which normally hold the tumbler 63 inwardly to move into the openings 14 when the middle sleeve is rotated relative to the inner sleeve.

80 An auxiliary tumbler carrier member or "lip" 63 is rotatably supported on ring 30' and is held from longitudinal displacement by sleeve 51 and collar 20. This member carries a tumbler 65 which is so rotated relative to ring 30' that it will normally ride upon the cylindrical surface 66 of the ring. The end tumbler 65, however, largely overlies the inner ends of the grooves in ring 30'.

85 As above stated lip member 63 is rotatably mounted upon ring 35. Obviously this member is rotated into alignment with tumbler carrier member 61 when the key is to be inserted into the key station. If, however, the key has been tampered with or undue play has arisen from wear which might permit manipulation of the key and the watchman might transmit a signal without inserting the key in the various stations, the longitudinal displacement of the lip 63 would permit tumbler 65 to drop into a groove in ring 30', thereby locking the lip into position and requiring repair or replacement of the key and thus preventing improper use thereof.

90 Fig. 7 shows a modified form of sleeve 4 wherein circumferential grooves 67 are provided and which guide tumbler members 53 in their rota-

tion about the sleeve. The bottoms of the grooves 57 are provided with openings that are co-extensive in width with the width of the groove, such openings being arranged in any desired sequence or combination in order to obtain the combination of settings desired in the signal system.

In Fig. 9 is shown an improved station comprising a part of this invention. This key station 10 comprises a suitable housing 68 having base member 69 and a cover member 10 which is provided with suitable opening 71 for insertion of the key member above described. The base 69 is provided with a recess 72 to receive key stop 15 when the key is inserted at the station and to limit rotative movement of the register in the station. Insertion of the key into a key station will cause the ball tumblers 73 of the combination of that station to depress the corresponding 20 tumblers 53 in the housing 61. Guide springs 74 and 75 are suitably secured in housing 68 to contact the sides of the tumbler housing 61 upon insertion of the key into the station. These 25 springs are unsymmetrically positioned relative to the path of travel of the key, spring 74 being in a position so that the instant the key is inserted at the station and the tumblers 53 are released by ball tumblers 73 tumbler housing 61, together with its associated tumblers 53, sleeve 30 30 51, and intermediate sleeve 30 are canted and cannot be turned against the force exerted by the spring 74 and be withdrawn from the station until tumblers 53 are located in the combination 35 for which that station is set. When the handle 2 and associated parts are turned sufficiently for the tumblers 53 to engage the openings in the inner sleeve 4, the handle, the sleeves and the housing become interlocked and the register may then be turned against the tension of the spring 74 until the tumbler housing 61 is in alignment with the opening 71 of the key station whereupon the register can be withdrawn ready for insertion into the next key station in which the above described operation is repeated. 40 45 This feature effectively prevents insertion of a key to release the tumblers and then slightly turning the handle to retain the tumblers in released position preliminary to withdrawal and further setting of the key manually in order that a central station signal may be sent without a 50 complete traverse of the intervening key station.

While the foregoing is a description of the preferred form of our invention, we do not desire to be limited thereby but only by the appended 55 claims interpreted in the light of the description.

What we claim as new is:

1. In a registry system a register comprising an outer cylindrical sleeve provided with inwardly, spring pressed tumblers, a middle tumbler guiding sleeve within said outer sleeve and provided 60 with a series of openings into which said tumblers project, an inner cylindrical tumbler engaging sleeve rotatably mounted within said second sleeve, and a shoulder and pin connection 65 between said sleeves and shank so arranged that the shank and the sleeves are fixed against relative axial displacement, said inner sleeve being provided with a series of axially elongated perforations to be selectively engaged by the tumblers. 70

2. In a registry system a register comprising an outer cylindrical sleeve provided with inwardly, spring pressed tumblers, a middle tumbler guiding sleeve within said outer sleeve and provided with a series of openings into which 75

said tumblers project, an inner cylindrical tumbler engaging sleeve rotatably mounted within said second sleeve, said inner sleeve being provided with a series of perforations to be selectively engaged by the tumblers, and a shoulder and pin connection securing said sleeves in fixed axial relation. 5

3. In a registry system, the combination of a register having registering means comprising an inner cylindrical tumbler engaging member provided with elongated tumbler engaging openings corresponding to different registering positions, tumbler carrying means rotatably mounted thereabout, a middle tumbler guiding sleeve intermediate said member and means, means for retaining said member and tumbler carrying means in assembled relation, and means for rendering the register inoperative upon relative axial movement of said member and tumbler guiding sleeve, said last mentioned means comprising an additional tumbler carrier rotatable about the middle tumbler guiding sleeve and adapted to make locking engagement therewith upon predetermined relative axial displacement. 10 15 20

4. In a registry system, the combination of a register having registering means comprising a tumbler engaging member provided with tumbler engaging openings in one portion of said member, said openings corresponding to different registering positions and tumbler engaging peripherally spaced grooves in another portion of said member, tumbler carrying means rotatably mounted about said first mentioned portion and a second tumbler carrying means rotatably mounted about said grooved portion of said sleeve 30 35 member, said last mentioned means having a tumbler normally out of register with said grooves, said spaced grooves being adapted to receive the tumbler of the second tumbler carrying member upon axial displacement thereof relative to the member. 40

5. In a register an inner cylindrical tumbler engaging sleeve provided with tumbler engaging openings and a reduced end section having a radial opening adjacent the end thereof, a cylindrical tumbler guiding sleeve rotatably mounted upon said first mentioned sleeve, said guiding sleeve having an inwardly extending shoulder encircling the reduced end section of the tumbler engaging sleeve and contacting the shoulder formed by reduction of the end section, a pin fixed in said radial opening at the end of said tumbler engaging sleeve whereby said sleeves are axially fixed in assembled relation, a tumbler carrying sleeve surrounding the guiding sleeve, 55 and a second tumbler carrying member surrounding the end of the tumbler guiding sleeve and having a tumbler adapted to make locking engagement with the last mentioned sleeve upon relative axial movement therewith. 60

6. In a registry system a register comprising a tumbler carrying sleeve, a cylindrical tumbler engaging sleeve within the tumbler carrying sleeve, a tumbler guiding sleeve intermediate said sleeves, said tumbler engaging sleeve having openings 65 to be engaged by the tumblers in the first mentioned sleeve whereby the register is locked in predetermined position by station actuating means, a second tumbler carrying means coaxially positioned adjacent said first mentioned sleeve 70 and means for locking said second mentioned tumbler means in a fixed position upon axial displacement thereof from normal position.

7. In a registry system a register comprising an outer cylindrical tumbler carrying sleeve, a mid- 75

idle tumbler guiding sleeve within said outer sleeve and provided with a series of openings into which the tumblers project, a sleeve rotatably mounted within said guiding sleeve and provided with 5 openings to be selectively engaged by the tumblers carried by said means, a second tumbler carrying means rotatably mounted upon said last mentioned sleeve adjacent said tumbler carrying sleeve, and means for locking said second tumbler carrying means in a fixed position upon 10 longitudinal displacement thereof from normal position.

8. In a registry system, a register actuating station comprising a case, said case being provided on its inner end with a recess for receiving a lip on the end of the inner perforated sleeve of a register, a cylindrical member fixed within said station to enter the perforated sleeve of the register, said member having spring pressed ball 15 tumblers for releasing the tumblers of a register inserted into said station and spring means for engaging and canting the tumbler carrying means of a register when the register is inserted into the 20

station and for holding the tumbler carrying means in canted position until the carrier is locked in position to be actuated by the next station.

9. In a registry system, a register having two 5 tumbler carrying members, a middle tumbler guiding sleeve and an inner cylindrical tumbler engaging sleeve, one of said tumbler carrying members being movable with the tumbler guiding sleeve and adapted to selectively position said 10 member on the inner sleeve upon control by a register actuating station, the other of said tumbler carrying members being rotatable about the guiding sleeve and having a tumbler normally out of register with spaced peripheral grooves in 15 said sleeve but adapted to enter one of said grooves and to lock the last mentioned tumbler carrying means in a fixed position upon the register upon axial displacement of said means from normal position. 20
